UNITED STATES PATENT OFFICE.

JOHN MACAULEY COONEY AND HARRY LEE TOTTEN, OF SHERMAN, TEXAS, ASSIGNORS TO MERGENTHALER LINOTYPE COMPANY, A CORPORATION OF NEW YORK.

LINOTYPE-DISTRIBUTER.

SPECIFICATION forming part of Letters Patent No. 759,501, dated May 10, 1904.

Application filed June 24, 1903. Renewed March 10, 1904. Serial No. 197,440. (No model.)

To all whom it may concern:

Be it known that we, JOHN MACAULEY COONEY and HARRY LEE TOTTEN, residing at Sherman, in the county of Grayson and State 5 of Texas, citizens of the United States, have jointly invented certain new and useful Improvements in the Distributing Mechanism of Linotype-Machines, of which the following is a specification, reference being had to the accompanying drawings, forming a part hereof.

Our invention has reference more particularly to commercial linotype-machines of the general organization represented in Letters Patent of the United States No. 557,000, dated 15 March 24, 1896. Machines of this class include a series of circulating matrices stored normally in an inclined channeled magazine, from which they are delivered one at a time in the required order, assembled in line, presented to the face 20 of a mold to form type characters on a slug cast therein, and finally lifted and returned through a distributing mechanism to the upper end of their appropriate magazine-channels. Each magazine is provided across its upper end with a channeled throat or entrance forming an upward continuation of the magazine proper and terminating immediately below the distributor, so that the matrices falling from the distributor into the respective channels of the throat will be guided thereby into the corresponding channels in the magazine. The magazine is removable from the machine, so that it may be withdrawn from the rear and replaced by another containing matrices 25 for a different type-face, this interchange of magazines frequently taking place at short intervals.

Heretofore it has been the practice to hinge the throat or "channel-entrance," so called, 40 permanently to the upper end of the magazine, so that it was necessary to provide a throat for each magazine and to remove the throat with the magazine when the latter was taken from the machine. When the magazine was 45 to be detached, the hinged throat-piece added to the weight and to the labor of the attendant, and being liable to fall out of position was in danger of having its partitions bent and rendered inoperative.

The object of our invention is to avoid the 50 necessity of providing a mouthpiece for each magazine; also, to avoid the necessity of removing the mouthpiece from the machine when the magazine is removed.

To this end it consists in movably connecting the throat to the frame of the machine in such manner that it may be instantly brought into operative relation to the magazine or moved away therefrom and out of its path.

In the drawings we have represented our invention in its preferred form as practically applied by us to the commercial Mergenthaler machine, the throat being supported by arms of a frame hinged or pivoted to the main frame.

With the exception of the parts herein shown 65 and described the machine may be in all respects of any ordinary or approved construction.

Referring to the drawings, Figure 1 is a side elevation of the distributing mechanism and 70 the upper end of the magazine of a Mergenthaler machine. Fig. 2 is a perspective view of the swinging frame or support for the throat or channel-entrance. Fig. 3 is a perspective view of details hereinafter explained. 75 Fig. 4 is a vertical section from front to rear through the magazine and distributing mechanism shown in Fig. 1. Fig. 5 is a perspective view of one of the latch-pins. Fig. 6 represents a longitudinal section through one end 80 of the swinging throat-supporting frame.

Referring to the drawings, 1 represents the ordinary inclined matrix-carrying magazine, occupying a fixed position in the main frame, but removable therefrom at will. This magazine consists of top and bottom plates, channeled longitudinally, as usual, to receive and guide the matrices falling from the distributor.

2 represents the throat or channel-entrance, 90 consisting of a light framework, having the usual series of upright channels or partitions, between which the matrices descend when released from the distributor-bar 40, along which they are carried by the feed-screws 41 95 in the usual manner. This throat is arranged to fit at its lower end closely against the upper end of the magazine, of which it forms a

continuation. It extends thence rearward and upward, so that the matrices falling vertically from the distributor may enter the throat and pass between its partitions into the magazine 5 below. Heretofore this throat 2 has been hinged directly to the frame of the magazine, so as to be thereby supported and removed therewith, as heretofore mentioned.

In carrying our invention into effect we dispense with the hinge connection between the throat and the magazine and connect the lower end of the throat by horizontal pivot-pins 16 to the lower ends of the two similar arms 4 and 5, which are extended upward and rearward and mounted at their upper ends on a horizontal rod 6, secured to brackets 9, bolted to the top of the main frame, this arrangement permitting the arms to swing upward, carrying with them the throat 2 from the operative position shown in full lines in Figs. 1 and 4 to the position shown by dotted lines in Fig. 1, the throat being in this manner carried wholly out of the way of the magazine, so that the latter may be withdrawn through 25 the rear side of the frame without interference.

The arms 5 are preferably connected by cross-rods 7 and 8, as shown in Fig. 2, the several parts constituting a rigid frame for the support of the throat or channel-entrance.

In order to counterbalance the weight of the throat and swinging frame in whole or in part as the throat is thrown upward to an inoperative position, we propose to combine 35 with the swinging frame counterbalancing devices, preferably in the form of spiral springs 11, coiled around the pivot-rod 6, each having one end shaped to exert a lifting effect on the cross-rod 7 of the swinging frame, while 40 the other end is seated in a collar 13, adjustably secured on the rod by a screw 14, which may be turned at will to vary the tension and the lifting effect of the spring.

The throat or channel plate may be secured 45 rigidly to the lower ends of the swinging arms 4 and 5, in which case access is gained to the upper end of the magazine and the distributing devices by swinging the frame backward and upward, as above described. In order, 50 however, to render access to the magazine easier and more speedy, we prefer to connect the throat at its lower end to the supporting-arms 4 and 5 by the pivot-pins 16, already referred to, this arrangement permitting the 55 throat to be turned backward, as indicated by dotted lines in Fig. 4, without disturbing the position of the supporting-arms. Each of the arms is provided at its lower end with a hollow screw or sleeve 17, held in place by a nut or 60 sleeve 17^x. The latch-pin 18 extends through the parts 16 and 17 and is provided at one end with a lateral arm or handle 19, extending outward through a cam-slot 20 of the sleeve 17, so that by turning the handle of the pin 18 the 65 latter may be moved endwise.

The hollow screws 17 serve as pivots to connect the throat or channel-entrance to the supporting-arms 4 and 5. After the throat is swung downward to its operative position against the lifting tendency of the springs the pins 18 are turned inward, so that their inner ends engage, as shown in Fig. 4, in the sides of the magazine-frame, thus holding the parts in operative relations.

The throat 2 may be held closely against the magazine by any suitable confining device—for example, by a spring 21, secured at one end to arm 22 of the throat and at the opposite end to arm 23, which is attached to arm 4 of the swinging frame, as shown in Figs. 1, 2, and 4. 80 The arm 23 also acts as a stop for the throat when turned back to give access to the magazine.

It will be observed that when the hinged frame and throat are thrown upward, as before 85 described, the upper end of the magazine is left free and without any obstruction in the way of its removal, so that it may be removed from the machine, leaving the throat behind. When another magazine is substituted, the 90 throat may be instantly turned down into operative relation thereto.

When the magazine is removed from the machine, it is desirable to prevent the accidental escape of the matrices from its upper end 95 in the event of its being overturned. For this purpose we extend a gate or guard 24 across the upper end of the magazine, providing it at the ends with supporting-arms pivoted at 25 to lugs or brackets on the top of the magazine, this arrangement permitting the guard to be dropped down, so as to partly overlap the end of the magazine and prevent the escape of matrices, and also permitting it to be thrown upward, as shown in Fig. 4, clear of the magazine-channels, so that the matrices may pass beneath it into the magazine. This hinged guard or gate is provided with a forwardly-extending arm 27, urged upward by an underlying spring 100 28. When the throat or channel-entrance is 110 in operative position, the guard or gate bearing on its upper side is pushed upward thereby and maintained in an elevated position, as shown in Fig. 4, to permit the free entrance of the matrices to the magazine. When, however, the throat is moved away from the magazine, the guard or gate immediately falls into 115 position to confine the matrices, as previously explained. The thumb-screw 29 may be seated in a bracket on the magazine to bear upon the arm 27 of the gate for the purpose of holding it out of action; but this is not a necessary feature of the invention.

The essence of the invention resides in supporting the throat or channel-entrance independently of the magazine and in such manner that it may remain on the machine when the magazine is removed, and it will be understood by the skilled mechanic that the details may be widely modified without passing 120 130

beyond the limits of our invention, which includes any form of hinged, jointed, or equivalent support which will permit the channel to be moved into and out of its operative position independently of the magazine. It will also be understood that the gate or retaining device at the upper end of the magazine may be widely modified in form without changing its form of action.

10. What we claim as our invention is—

1. In a linotype-machine and in combination with the main frame, a removable magazine, and a magazine throat or entrance sustained from the main frame independently of the magazine.

15. 2. In a linotype-machine, the combination of a main frame, a stationary magazine therein, and a throat for the magazine connected to the main frame and movable independent of the magazine.

20. 3. In a linotype-machine, the combination of a magazine, a throat or entrance therefor, and a swinging support for the throat independent of the magazine.

25. 4. In a linotype-machine, a magazine, an entrance-throat therefor, and a support for the throat pivoted thereto and also pivoted on a fixed axis, whereby the throat is permitted to turn independently of the support to give access to the magazine, and also permitted to swing bodily with the support when the magazine is to be removed.

30. 5. In a linotype-machine, the combination of a main frame, a secondary or swinging frame hinged thereto, and a magazine-throat carried by the swinging frame.

35. 6. In a linotype-machine, the combination of a main frame, a swinging frame hinged thereto, and a magazine-entrance pivoted to the swinging frame.

40. 7. In a linotype-machine, the combination of a main frame, a magazine, 1, and magazine-throat, 2, a swinging frame carrying and supporting the throat, and counterbalancing devices coöperating with the swinging frame.

45. 8. In a linotype-machine, the combination of the magazine, its throat, a swinging support for said throat, spring connections tending to throw the throat and its support away from their operative position, and means for locking the support and throat in place.

50. 9. In a linotype-machine, the combination of a main frame, a removable magazine, a

throat therefor, and means for movably supporting said throat from the frame independently of the magazine. 55

10. In a linotype-machine, the main frame, a magazine, a swinging frame jointed to the main frame, the magazine-throat jointed to the swinging frame, and a spring connecting the throat and swinging frame and tending to hold the former in operative relation to the magazine.

11. In a linotype-machine, in combination with a removable magazine, a gate or guard movably connected to its upper end to prevent the accidental escape of the matrices when the magazine is separated from the machine.

12. In a linotype-machine, the combination of a magazine, a movable guard mounted on its upper end to prevent the accidental escape of matrices, and a movable magazine-throat adapted to throw the guard out of action.

13. In a linotype-machine, the combination of the magazine, the guard or gate hinged to its upper end, and an entrance-throat, 2, acting when in operative position to keep the gate out of action.

14. In a linotype-machine, the combination of a magazine, a movable gate mounted in its upper end to prevent the accidental escape of matrices, a spring tending to hold the gate in operative position, and means on the magazine for throwing and holding the gate out of action.

15. In a linotype-machine, the combination of a magazine, a swinging frame independent of the magazine, a magazine-throat pivoted to said frame, means for locking the swinging frame in position, and means for holding the throat in operative relation to the magazine when the frame is locked as described.

16. In a linotype-machine, in combination with the magazine, the swinging frame, the magazine-throat carried by said frame, and devices for locking the swinging end of the frame to the magazine. 95

In testimony whereof we affix our signatures in presence of two witnesses.
